AUTOMATIC CARTON SEALING MACHINE

Elmer B. Voss, Alton, Ill., assignor to Owens-Illinois Glass Company, a corporation of Ohio

Application May 20, 1936, Serial No. 80,827

6 Claims. (Cl. 93—2)

The automatic carton sealing apparatus comprising the present invention is primarily adapted for use in sealing the tops of packed cardboard cartons of the type employing overlapping pivoted 5 or folding top closures which are united by any of various adhesives, although the principles of the invention are, with or without modification, applicable to other uses and the apparatus may, if desired, be employed for sealing other types 10 of cartons.

The principal object of the invention is to provide a carton sealing apparatus designed to receive cartons of varying size at one end thereof and which will, without modification or adjustment of the apparatus, convey the cartons through the machine and by the application of pressure to the tops of the cartons, secure the tops against movement relative to the cartons during setting of the adhesive, and effectively seal 20 the same, and thereafter discharge the cartons at the other end thereof in permanently sealed condition.

It is another object of the invention to provide a carton sealing apparatus in which the pressure 25 applied to the tops of the cartons for the purpose of sealing the same is uniform and evenly applied and does not vary when cartons of different sizes are fed to the apparatus, while additionally, the time element involved in the application of pressure 30 sure to the carton tops is maintained substantially constant regardless of the varying size of the cartons.

Yet another object of the invention is to provide an apparatus for sealing cartons by the application 35 of pressure to the tops thereof in which the pressure is applied to and removed from the tops gradually, thus eliminating shock and consequent damage to the cartons or to the contents thereof.

The provision of a carton sealing apparatus 40 which is comparatively simple in its construction, being comprised of relatively few moving parts, yet which is entirely automatic in its operation; one which is rugged and durable and therefore 45 is unlikely to get out of order; and one which may be manufactured inexpensively, are further desirable features which have been borne in mind in the production and development of the present invention.

Other objects will be in part apparent and in part pointed out hereinafter.

In the accompanying five sheets of drawings:

Fig. 1 is a side elevational view of a carton sealing apparatus in the form of a machine manu-

factured in accordance with the principles of the present invention;

Fig. 2 is a front view of the machine illustrated in Fig. 1 and showing the feeding end thereof;

Fig. 3 is a rear view of the machine showing the discharge end thereof;

Fig. 4 is a fragmentary sectional view taken substantially along the line 4—4 of Fig. 3 in the direction indicated by the arrows and confined to the discharge end of the apparatus;

Fig. 5 is a sectional view taken along the line 5—5 of Fig. 4 in the direction indicated by the arrows;

Fig. 6 is a fragmentary sectional view taken substantially along the line 6—6 of Fig. 2 in the direction indicated by the arrows and confined to the receiving end of the apparatus;

Fig. 7 is a sectional view taken substantially along the line 7—7 of Fig. 6 in the direction indicated by the arrows;

Fig. 8 is a top plan view of one of a series of pressure applying elements employed in connection with the present invention;

Fig. 9 is a fragmentary front elevation of the element shown in Fig. 8;

Fig. 10 is a side view of the disclosure made in Fig. 9; and

Fig. 11 is a fragmentary sectional view, partially diagrammatic in its representation, taken transversely through an endless pressure applying carrier system incorporated in the apparatus.

In all of the above described views, like characters of reference are employed to designate like parts throughout.

Referring now to Fig. 1, the machine involves in its general organization an endless conveyor assembly designated in its entirety at 10 for receiving cartons or other packages 12 to be sealed and for conveying them through the apparatus. Operatively associated with the conveyor assembly 10, and designated in its entirety at 13, is an endless sealing carrier assembly 35 designed for applying pressure to the tops of the moving cartons to seal the same by holding said tops and cartons together during setting of the adhesive as they move through the apparatus on the endless conveyor assembly 10. The endless conveyor system 10 and the endless carrier system 13 (Fig. 1) are mounted in superimposed relationship in a stationary supporting structure 40 forming a part of the machine and consisting of opposed pairs of vertically disposed upper and lower front supporting members 14 and 16 and similarly opposed pairs of upper and lower rear supporting members 18 and 20, one pair of such 45

50 forming a part of the machine and consisting of opposed pairs of vertically disposed upper and lower front supporting members 14 and 16 and similarly opposed pairs of upper and lower rear supporting members 18 and 20, one pair of such 55

members being disposed at each corner of the machine. The members 14, 16, 18 and 20 are in the form of comparatively wide structural plates which are suitably held in position in the machine by means of a plurality of longitudinal and transverse structural members 22 and 24 respectively. A plurality of vertically disposed reinforcing members 26 extend between the longitudinal members 24 at spaced points therealong, the number of such members employed being arbitrary, and depending upon the length of the machine.

The conveyor assembly 10 is preferably of the endless chain and slat type and consists of a plurality of parallel longitudinal chains 28 (see Figs. 4 and 5), the individual links 30 of which serve to support therebetween a plurality of transverse conveyor elements 32 or slats upon which the cartons 12 are adapted to be supported and conveyed through the machine.

The conveyor chains 28 are supported at the front end of the machine upon a plurality of sprockets 34 (see Figs. 6 and 7), corresponding in number to the number of chains 28 employed, and mounted for rotation in unison upon a transverse shaft 36 journaled in bearings 38 (see Fig. 1) suitably supported on the lower front supporting members 16. Similarly, the conveyor chains 28 are supported at the rear of the machine by means of a plurality of sprockets 40 (see Figs. 4 and 5), likewise mounted for rotation in unison upon a transverse shaft 42, journaled in bearing members 44 (see Fig. 1), mounted upon the lower rear supporting members 20. A plurality of idler sprockets 46, mounted upon a transverse shaft 48, rotatably carried by the supporting members 20, engage the respective chains 28 adjacent the bottom of the machine and at the rear thereof. Similar idler sprockets 50 are carried by a transverse shaft 52 mounted for rotation between the front supporting members 16 adjacent the bottom thereof. These latter sprockets 50 are designed to engage the respective chains 28 and take up any existing play that may be encountered in the conveyor. Accordingly, the opposite ends of the shaft 52 are rotatably journaled in bearing members 54 which are slidably mounted in guide members 56 carried in any suitable manner by the supporting members 16. Adjusting screws 58 extend through threaded portions 60 of the guide members 56 and engage the bearing members 54 to normally urge the same forwardly and take up any existing play in the conveyor chains 28.

In order to support the operative conveying portion of the endless conveyor 10 between the front and rear sprockets 34 and 40 respectively, a conveyor table is provided. This table is in the form of a plurality of longitudinally extending channel-shaped tracks 68 (see Fig. 5) corresponding in number to the number of conveyor chains 28, each individual chain 28 being slidably supported in a corresponding track. In order to support the tracks 68 in operative load-carrying position, a pair of longitudinally extending structural members 70 have their opposite ends supported by the front and rear supporting members 16 and 20 and a plurality of transverse angle pieces 72 extend across the machine immediately below the level of the conveyor top and have their opposite ends secured to these members 70. The angle pieces 72 support the tracks 68 in spaced relationship in the conveyor assembly 10.

The endless sealing carrier assembly 13 is

positioned in the machine directly above the conveyor assembly 10 and has associated therewith instrumentalities for applying uniform pressure to the tops of the cartons 12 as they pass through the machine on the conveyor assembly 10.

The carrier assembly is comprised of a pair of endless chains 74 (best illustrated in Figs. 4, 8, 9 and 11), the corresponding individual links 76 of which support therebetween a plurality of transversely extending guide bars 78. These 10 guide bars 78 are identical in construction and each bar is provided with a pair of integrally formed bosses providing guides 80 medially of its ends. Slidably extending through the guides 80 of each guide bar 78 is a pair of guide rods 82, 15 each having enlarged heads 84 at one end thereof. The opposite ends of each pair of guide rods 82 are anchored as at 86 (see Fig. 9) in an elongated pressure member 88. The pressure members 88 or presser bars are in the form of comparatively heavy transversely extending bars designed to engage the tops of the cartons 12 and by their inherent weight, apply sealing pressure thereto in the manner to be more fully described hereinafter.

The endless carrier chains 74 are supported adjacent the rear of the machine upon a pair of sprockets 90 (see Fig. 4) suitably spaced apart and mounted for rotation in unison on a transversely extending shaft 92 journaled in bearings 94 (see Fig. 1) carried by the upper rear supporting members 18.

The carrier chains 74 are supported adjacent the front of the machine upon a pair of sprockets 96 (see Fig. 7) mounted in spaced relation for rotation in unison upon a transversely extending shaft 98 journaled at opposite ends in a pair of 35 slideable bearing blocks 100 (see Fig. 1) slidably supported by the upper front supporting members 14. Each bearing block 100 is integrally 40 formed with a longitudinally adjustable guide member or frame 102 (see Figs. 6 and 7), which guide frames are spaced apart and occupy opposed positions at the forward end of the carrier assembly 13. These guide frames are substantially 45 parallel and are provided with arcuate guides or 50 grooves in the form of tracks 104 which cooperate with the pressure members 88 (see Fig. 9) to direct them into sealing contact with the tops of moving cartons 12. Toward this end each pressure member 88 is provided at its ends with a pair of oppositely extending pins 106 carrying rollers 108 on their outer ends, which rollers are engaged by and confined in the grooves 104 when the pressure members 88 in their travel, reach the forward end of the conveyor 13. A pair of 55 adjusting screws 110 (see Fig. 6) extend through threaded openings 111 provided in the upper supporting members 14 and engage the bearing blocks 100. Thus, when any existing slack in the carrier chains 74 is taken up, the guide frames 60 102 are simultaneously and automatically adjusted for proper cooperation with the guide pins and rollers 106, 108.

In order to support the medial portions of the conveyor chains 74 in their endless travel, a plurality of angle pieces 112 (see Fig. 11) are supported longitudinally in the machine between the upper supporting members 14 and 18. Similar angle pieces 114 providing tracks for supporting the pressure members 88 during their inoperative forward travel in the carrier assembly 13, extend longitudinally between the supporting members 14 and 18 in a plane substantially level with the upper ends of the grooves 65 70 75 104. The tracks 114 (see Fig. 6) are substan-

tially in alignment with the upper end of the grooves 104 or tracks and thus the supporting pins and rollers 106, 108 carried by the pressure members 88 are guided into the grooves 104 as 5 they approach the limit of their forward travel.

The lower ends of the grooves 104 provided in the guide frames 102, terminate above the level of the tops of the cartons 12 resting on the conveyor assembly 10. Thus, the pressure members 10 88 are maintained in elevated position above the carton tops at the commencement of their rearward travel in the carrier assembly 13. In order to prevent the pressure members 88 from immediately dropping onto the tops of the cartons 15 12 when they leave the arcuate grooves 104 at the commencement of their rearward travel, the lower edges of the grooves 104 terminate in downwardly inclined cam surfaces 116 upon which the pins and rollers 106, 108 are adapted 20 to descend gradually and without acceleration. Such descent occurs due to the action of gravity exerted by the potential weight of the pressure members 88 which are slidably guided by the carrier bars 78. It will be seen that regardless 25 of the size, and particularly the height, of the cartons introduced onto the conveyor assembly 10, the pressure members being guided by the pins and rollers 106, 108, in the groove 104, will be restricted from gravitational acceleration and 30 will descend uniformly upon an incline as determined by the inclined cam surface 116 and come to rest on the top of the foremost carton in the machine.

The pressure members 88 are adapted to apply 35 their weight to the tops of the cartons 12 during a major portion of the rearward travel of the cartons upon the conveyor assembly 10. As the sealed cartons emerge from the machine at the rear thereof, means are provided for elevating the pressure members from contact with the carton tops. Toward this end a pair of opposed guide frames 118 (see Fig. 4) similar 40 in their design to the guide frames 102, are secured to the inner opposed faces of the upper supporting members 18. These guide frames 118 are provided with arcuate grooves 120, the upper 45 ends of which are substantially in alignment with the tracks 114 and the lower ends of which terminate at points well above the tops of the 50 cartons 12. A pair of endless chains 119, each mounted on sprockets 121 and 123, suitably journaled in the opposed supporting members 20 and 18 respectively on the inner sides thereof, occupy 55 respective positions in alignment with the rollers 108 carried by the pins 106 that extend from opposite ends of each pressure member 88. The rollers 108 engage these chains 119 as the cartons 12 pass between the same and are carried upwardly to enter the arcuate grooves 120. The 60 chains 119 are driven by a chain and sprocket 150, which sprocket is mounted on shaft 141. The pressure members 88 are thus elevated as they approach the end of their rearward travel and the pressure applied by them to the carton 65 tops is gradually removed.

In order to effect relatively stationary contact between the pressure members 88 and the tops of the cartons 12 to prevent shifting of the carton tops during setting of the adhesive, the 70 endless conveyor assembly 10 and the endless carrier assembly 13 are synchronized for equal linear travel. Accordingly, an electric motor 130 (see Fig. 1) preferably of the variable speed type, is operatively connected through a belt and pulley 75 system 132 to a drive shaft 134. This drive

shaft 134 is operated through a gear reduction mechanism 136 having a drive shaft 138 and imparts motion to the endless conveyor assembly 10 through a system of chain and sprocket mechanisms 140, 142. The endless carrier assembly 13 is driven through reversing gears 144 and 145 having driving engagement with a chain and sprocket mechanism 148. The reversing gear 145 is mounted on a stub shaft 146 which is carried by bracket 147 on the frame member 10 20. The number of teeth provided on the various chain and sprocket mechanisms are calculated according to well known engineering principles so that the relative speed of the conveyor system 10 and of the carrier system 13, in 15 actual linear travel of the moving endless parts thereof, will be equal.

It is to be noted that the adjustable pressure members 88 when in operative sealing position upon the tops of the cartons 12, are positioned 20 relatively close to each other. Because of this fact and because of the fact that the pressure members 88 are substantially equal in weight, equal pressure is applied to the areas of the carton tops to be sealed, regardless of the height 25 of the cartons and regardless of their size. By the use of a variable speed motor 130, various engineering exigencies, such as the type of adhesive employed in sealing the carton tops, the 30 temperature and humidity of the air, and the character of the material from which the cartons are formed may be compensated for.

Modifications may be resorted to within the spirit and scope of the appended claims.

I claim:

1. In a machine for sealing cartons or the like, means for conveying the cartons to be sealed through the machine at a predetermined rate of speed from a point of entry to a point of discharge, a plurality of pressure members mounted 40 above said cartons and movable in the direction of travel of the same, said pressure members being adapted to descend by gravity into relatively stationary contact with the tops of said cartons, means adjacent said point of entry for guiding 45 said pressure members during such descent, and means for removing said pressure members from contact with the tops adjacent said point of discharge.

2. In a machine for sealing cartons or the like, 50 means for conveying the cartons to be sealed through the machine at a predetermined rate of speed from a point of entry to a point of discharge, a plurality of pressure members mounted above said cartons and movable in the direction of travel of the same and at the same rate of speed, said pressure members being adapted to descend into relatively stationary contact with the tops of said cartons, means adjacent said point of entry for guiding said pressure members during their descent, while at the same time preventing gravitational acceleration thereof, and guide means for removing said pressure members from contact with the tops adjacent said point of discharge.

3. In a machine for sealing cartons or the like, 55 an endless conveyor assembly for conveying cartons to be sealed through the machine from a point of entry to a point of discharge, an endless carrier assembly positioned above said conveyor assembly, including a plurality of vertically movable pressure members, said pressure members being adapted to descend by gravity into relatively stationary contact with the tops of cartons introduced into said machine, means adjacent 60

said point of entry for guiding said pressure members during their descent, guide means positioned adjacent said point of delivery for elevating said pressure members from contact with 5 said carton tops, and means for driving said endless conveyor assembly and said endless carrier assembly at the same rate of linear travel.

4. A machine for sealing the tops of cartons or the like comprising in combination, a pair of 10 endless carriers mounted one above the other for synchronized travel at equal rates of speed, the lowermost carrier being adapted to receive thereon cartons to be sealed for conveying them through the machine, the uppermost carrier including a plurality of slidable pressure members 15 movable into and out of the plane of the carrier and endlessly movable with the carrier, said pressure members upon movement in the direction of travel of said cartons being adapted to move out 20 of the plane of said carrier by gravity and rest upon the tops of said cartons to seal the same, and means for retracting said pressure members upon completion of their sealing operation for movement in the opposite direction.

25 5. A machine for sealing the tops of cartons or the like, comprising in combination a pair of endless carriers mounted one above the other for synchronized travel at equal rates of speed, the lowermost carrier being adapted to receive thereon 30 cartons to be sealed for conveying them through the machine from a point of entry to a point of discharge, the uppermost carrier including a plurality of slidable pressure members movable into and out of the plane of the carrier and

endlessly movable with the carrier, said pressure member upon movement in the direction of travel of said cartons being adapted to move out of the plane of said carrier by gravity and rest upon the tops of said cartons to seal the same, means positioned adjacent said point of entry for guiding said pressure members into engagement with the tops of said cartons, and means positioned adjacent said point of discharge for moving said pressure member out of engagement with said 10 carton tops. 5

6. In a machine for sealing the tops of cartons or the like, means for conveying the cartons to be sealed through the machine at a predetermined rate of speed from a point of entry to a point of 15 discharge, an endless carrier assembly positioned in the machine above said conveying means and including a longitudinally extending endless carrier having a plurality of pressure members movable into and out of the plane of the carrier and 20 endlessly movable therewith, said pressure members upon movement in the direction of travel of said cartons being adapted to move out of the plane of said carrier and rest upon the tops of 25 said moving cartons, a plurality of sprockets mounted upon a transverse shaft for supporting one end of said carrier, a pair of longitudinally adjustable bearing blocks in which the ends of 30 said shaft are journaled, and guide means carried by said bearing blocks and adjustable therewith for guiding said pressure members into relatively stationary contact with said carton tops.

ELMER B. VOSS.
